CLAIM

The ornamental design for a tray, as shown and described.

DESCRIPTION

FIG. 1 is a top perspective view of a first embodiment of a tray, showing our new design.

FIG. 2 is a bottom perspective view thereof.

FIG. 3 is a front elevational view thereof.

FIG. 4 is a rear elevational view thereof.

FIG. 5 is a left side elevational view thereof.

FIG. 6 is a right side elevational view thereof.

FIG. 7 is a bottom plan view thereof.

FIG. 8 is a top plan view thereof.

FIG. 9 is a top perspective view of another embodiment of a tray, showing our new design.

FIG. 10 is a bottom perspective view thereof.

FIG. 11 is a front elevational view thereof.

FIG. 12 is a rear elevational view thereof.

FIG. 13 is a left side elevational view thereof.

FIG. 14 is a right side elevational view thereof.

FIG. 15 is a bottom plan view thereof.

FIG. 16 is a top plan view thereof.

FIG. 17 is a top perspective view of another embodiment of a tray, showing our new design.

FIG. 18 is a bottom perspective view thereof.

FIG. 19 is a front elevational view thereof.

FIG. 20 is a rear elevational view thereof.

FIG. 21 is a left side elevational view thereof.

FIG. 22 is a right side elevational view thereof.

FIG. 23 is a bottom plan view thereof.

FIG. 24 is a top plan view thereof.

FIG. 25 is a top perspective view of another embodiment of a tray, showing our new design.

FIG. 26 is a bottom perspective view thereof.

FIG. 27 is a front elevational view thereof.

FIG. 28 is a rear elevational view thereof.

FIG. 29 is a left side elevational view thereof.

FIG. 30 is a right side elevational view thereof.

FIG. 31 is a bottom plan view thereof; and,

FIG. 32 is a top plan view thereof.

(Continued)

The broken lines showing certain markings and measurement lines are for the purpose of illustrating environmental structure and unclaimed subject matter and form no part of the claimed design.
